UNITED STATES PATENT OFFICE

2,564,481

MECHANICAL DEVICE TO SECURE WINDOW
PANE IN A WINDOW SASH

Charles P. Kegley, Pulaski, Va.

Application October 6, 1947, Serial No. 778,103

2 Claims. (Cl. 20—56.4)

1

My invention relates to windows and more particularly to a device adapted to secure glass panes or the like in a window sash.

The object of my invention is to provide a mechanical device for securing glass panes in a window sash, said means replacing the conventionally used putty.

Another object of my invention is to provide a device of the character indicated above which is adapted to be removed from the window sash and to be replaced again, permitting a glass pane to be set exchangeably in said sash.

A further object of my invention is to provide a device of the character indicated above which is adapted to engage the glass pane and the sash of a window in such a manner that the contact between the glass pane, the sash and the pane securing device is such, that the pane is being held securely but removably in position, and that any rattling of the glass pane and any leakage through the seams of contact is eliminated.

Other objects of my invention may appear in the following specification describing my invention with reference to the accompanying drawing illustrating a preferred embodiment of my invention.

It is, however, to be understood, that my invention is not to be restricted or limited to the exact construction and combination of parts described in the specification and shown in the drawing, but that such changes and modifications can be made, which fall within the scope of the claims appended hereto.

In the several figures of the drawing similar parts are designated by similar reference characters and

Figure 1 is a view in elevation of a window frame showing the application thereto of a pane securing device constructed in accordance with the present invention.

Figure 2 is a detail section taken substantially on the line 2—2 of Figure 1.

Figure 3 is a view in perspective of a portion of the glass securing device.

The device forming the subject matter of my invention is made from light sheet metal and has a body *a* of a substantially V-shaped cross section and consisting of an outer wing *10* and an inner wing *11*, which are pressed pretty tightly together.

A portion of the outer wing *10* is bent away from the inner wing *11* at an obtuse angle to form the narrow flange strip *12*.

On the edge of the inner wing *11* a narrow flange *13* is formed extending in the opposite

2

direction to the flange portion *12* of the outer wing *10* and at an angle somewhat smaller than 90°.

On the end of the flange *13* a bead *14* is formed by bending the metal so that it extends approximately parallel to and in the same direction as the flange portion *12* of the outer wing *10* and forms a shallow curved pressure member *15* for a purpose to be described later.

10 A thin rubber strip *16* is placed between the outer and inner wing *10* and *11* and is clampingly engaged and held in place by said wings. It extends along the pressure member *15*.

Each of the four members *17*, *18*, *19* and *20* of a window sash *b* is provided at its outer side with an inwardly extending rabbet *21*, against which rests a glass pane *22* fitting snugly into the sash *b*.

Inwardly from the rabbet *21*, each sash member is provided with a longitudinal groove *23* arranged so that the four grooves are forming a continuous rectangular groove, when the sash members *17*, *18*, *19* and *20* are assembled in any preferred conventional manner.

The above described pane securing device is then cut into two strips *24* fitting transversely into the window sash *b*, and the V-shaped body of each strip is forced into the groove *23* of one of the transverse sash members *17* and *19* respectively until the bead *14* abuts the sash *b*.

Two other strips *25* are then cut from the pane securing device, each strip fitting longitudinally into the window sash *b*. From each end of each longitudinal strip *25*, a piece of the body *a* and of the flange portion *10* of the outer wing *12* is cut off, so that the cut ends extend at right angles to the apex edge of the V-shaped body and each removed portion is as long as the width of the pressure member *15*.

Each end of each longitudinal pressure member is cut at an angle of 45°, and the bodies of the two longitudinal strips are forced into the grooves *23* of the longitudinal sash members *18* and *20* until the bead *14* abuts the sash *b*.

When the glass pane *22* is arranged in the sash *b* and the four strips *24* and *25* respectively of the pane securing device are inserted in the grooves *23* as described above the pressure members *15* are urged against the glass pane by the beads *14* abutting the sash *b*. The rubber strips *16* prevent the pressure strips from coming into direct contact with the pane, so that tight, firm, but resilient seams of contact are formed.

The pressure members *15* of the transverse strips *24* are adapted to extend across the entire width of the pane on account of the cut-back

ends of the V-shaped bodies *a* of the longitudinal strips *25*, and the bevelled ends of the pressure members of said longitudinal strips will be located so that they overlap the ends of the pressure members of the transverse strips.

The above description shows clearly that the device forming the subject matter of my invention holds a glass firmly and securely in position in a window sash, prevents any rattling noise caused by said window pane and forms leakage proof contact seams. In addition to that, the pane securing device can be easily removed and replaced so that the use of wire brads and putty is eliminated.

I claim:

1. A device for securing a glass pane in a window sash, comprising a metallic strip having a body portion of V-shaped cross section, the two sides of the body being in relatively close relation, one side of the body having a portion of its longitudinal edge directed laterally at an obtuse angle, the opposite side of the body having a portion of its longitudinal edge extended in the opposite direction at an acute angle, the said obtusely and acutely angled portions having a substantially parallel relation, and the outer edge of the said acutely angled portion having joined thereto an edge of a transversely curved resilient pressure member, the said pressure member curving inwardly and upwardly over and away from the acutely angled portion to which it is attached.

and overlying the obtusely angled portion, the joined edges of the acutely angled portion and said pressure member forming a contact bead for engagement with a surface of the rabbet when the said V-shaped body is inserted in a receiving slot in said surface whereby to flex the acutely angled portion to press the free edge of the resilient pressure member inwardly against the adjacent glass pane, the laterally directed, obtusely angled, edge portion of the said one side of said body bearing against the glass pane below the line of bearing of said pressure member therewith.

2. A device of the character described in claim 1, with a strip of elastic material having a portion of one longitudinal edge gripped between the said sides of the V-shaped body, the elastic strip extending upwardly across the convex side of the resilient pressure member to the free longitudinal edge of the latter.

CHARLES P. KEGLEY.
